DESIGN FOR A VANITY CASE OR SIMILAR ARTICLE

Emanuel J. Gerli, New York, N. Y.

Application April 14, 1941, Serial No. 100,375

Term of patent 3½ years

To all whom it may concern:

Be it known that I, Emanuel J. Gerli, a citizen of the United States, residing at 39 West 55th Street, in the city of New York, county of New York, and State of New York, have invented a new, original, and ornamental Design for a Vanity Case or Similar Article, of which the following is a specification, reference being had to the accompanying drawing, forming part thereof.

Fig. 1 is a top plan view of a vanity case or similar article showing my new design;

Fig. 2 is a bottom plan view thereof; and

Fig. 3 is an edge elevational view thereof.

I claim:

The ornamental design for a vanity case or similar article, substantially as shown.

EMANUEL J. GERLI.
